UNITED STATES PATENT OFFICE.

EDWARD C. ANGELL, OF NEW YORK, N. Y., ASSIGNOR TO SINGLE SERVICE BOTTLE CORPORATION OF NEW YORK, OF NEW YORK, N. Y., A CORPORATION OF NEW YORK.

APPARATUS FOR CLOSING AND SEALING CONTAINERS OR RECEPTACLES.

1,185,755.

Specification of Letters Patent.

Patented June 6, 1916.

Application filed August 21, 1914. Serial No. 857,833.

To all whom it may concern:

Be it known that I, EDWARD C. ANGELL, a citizen of the United States, residing in the borough of Manhattan, in the city, county, 5 and State of New York, have invented new and useful Improvements in Apparatus for Closing and Sealing Containers or Receptacles, of which the following is a specification.

10 This invention relates to apparatus for closing and sealing the top or open end of containers or receptacles made of paper, such as paraffin paper, for carrying liquids and the like, and which are commonly 15 known as "single service packages or containers" in which a sheet of paper is rolled into tubular form, preferably conical, with one end closed to constitute the bottom, and the other end or top adapted to be collapsed 20 and pinched together and secured in said position to secure the same.

It is the object of the present invention to provide an apparatus to collapse the open 25 end of such a container and apply a clamping strip thereto to close and seal the same, and to provide an apparatus of this type to simultaneously close and seal a series of containers supported upon a carrier in juxtaposed pairs.

30 In carrying out the invention I provide a carrier for a series of containers to support the same in juxtaposed pairs, means being provided to collapse the tops or open ends of the containers after which a 35 clamping strip is fed over the top of each container and simultaneously longitudinally folded or bent to be substantially of inverted-V shape in cross section. After a predetermined portion of the clamping strip

40 has been fed over the containers it is severed by a suitable cutter mechanism, when the container collapsing means is further operated to clamp the clamping strip on to the container and thereby close and seal the 45 same, after which the parts are returned to initial position and the carrier with the closed containers advanced and another portion of the carrier with another series of containers is brought into position to be 50 operated upon.

In the drawings accompanying and forming a part of this specification, Figure 1 is a side elevation of an apparatus illustrating an embodiment of my invention. Fig. 2 55 is a plan view of the apparatus shown in

Fig. 1. Fig. 3 is an end elevation showing the parts in normal position. Fig. 4 is a view similar to Fig. 3 but showing the parts in position after the end of the containers have been collapsed and the clamping strip 60 applied thereto. Fig. 5 is a detail side elevation of the clamping strip feeding and bending mechanism and showing the cutter mechanism in relation thereto. Fig. 6 is a detail side view of the clamping strip cutting mechanism. Fig. 7 is an end elevation illustrating a modified construction in which the head above the containers is fixed and the carrier for the containers is mounted to have movement toward and away from 70 the head.

Similar characters of reference designate like parts throughout the different views of the drawings.

In the embodiment of my invention illustrated in Figs. 1 to 4 of the drawings all of the mechanism is shown as mounted and supported by a framework or base (designated in a general way by A) and the operative mechanism is actuated from a main 75 driving shaft 10 driven from a suitable source of power as by a belt 11 passing around a pulley 12 fixed to the shaft 10. A series of containers C in juxtaposed pairs are supported upon a carrier (designated in 80 a general way by B) in the form of a conveyer supported upon rollers 13 and adapted to be intermittently advanced by suitable mechanism, not shown.

Supported above the containers upon vertical standards or columns 14 fixed in the base to have sliding movement is a head 15, said head being in the nature of a carrier for a series of bars 16, one pair for each pair of containers and one bar of each pair at 95 each side of a pair of containers, said bars having movement toward the containers to collapse the open or upper ends and for a purpose to be hereinafter described. The bars are normally maintained in position 100 away from the containers by springs 17. The head or carrier 15 is supported on the columns 14 to have movement toward and away from the tops of the containers and is normally maintained up from the containers 105 by rods 18 pivotally connected at one end to the head and at the other end carrying a roller 19 engaging with cams 20 fixed to shafts 21 driven by the main shaft 10 through worms 22 on said shaft and worm 110

wheels 23 on the shafts 21. When in its lowermost position the head rests and is supported upon collars 24 fixed to the columns 14.

5 After the head has been lowered with relation to the tops of the containers on the carrier and rests upon the collars 24 means carried by said head are actuated to collapse, or partially collapse, the open or 10 upper ends of the containers. this means consisting of a pair of bars 16 for each pair of containers and one bar of each pair located at opposite sides of a pair of containers. These bars are normally maintained in position 15 away from the containers by springs 17, one end of the springs connected to one bar of a pair and the other end to the adjacent bar of a succeeding pair. To impart movement to the bars to cause them to move 20 toward each other and collapse the containers therebetween the ends of the bars are beveled, as at 28, plungers 29 slidably mounted in the head having beveled heads 30, the beveled portion of the heads being 25 adapted to engage with the beveled portion of the bars as the plungers are moved inward thereby spreading a bar of adjacent bars apart and toward their companion bars, as will be readily understood from the 30 drawings. The plungers 29 are actuated by cams 31 fixed to the shafts 21, said cams co-operating with cam followers adjustably carried at one end of rocker arms 32 pivotally supported, as at 33, the other ends of 35 the arms having a slot connection 34 with the plungers 29.

As stated the collapsed ends or tops of the containers are closed and sealed by a clamping strip, preferably of metal, and to apply 40 this clamping strip I provide a series of rolls of flexible metallic strips S, one roll for each container on the carrier, said rolls being carried by arms 34' fixed to and projecting laterally from the projecting ends 45 of the standards 14. The clamping strip is intermittently fed above the containers and between the clamping bars 16 after the containers have been collapsed by the bars and longitudinally folded or bent to be substantially 50 of inverted-V shape in cross section. For this purpose there is provided for each strip a pair of rolls 36, 37, the periphery of the roll 36 being tapered or rounded and the roll 37 formed with an annular recess to conform to the shape of the periphery of the roll 36 and in which the latter engages. The periphery of the roll 36 and the recess in the roll 37 are preferably roughened or fluted to facilitate the 55 feeding of the clamping strip. It will be noted that a clamping strip is fed over each container of a pair from opposite sides. The feed rolls are actuated intermittently by gearing and pawl and ratchet mechanism 60 comprising pinions 38 rotatable in the pres-

ent instance with the lower rolls, gears 39 rotatably mounted on the head 15 meshing with said pinions, ratchet wheels 40 being connected to and rotating with the gears 39. The ratchets and gearing are rotated by 70 spring influenced pawls 41 pivotally carried by links 42 one end of which are pivotally connected to the axes of the rolls 36 and the other ends pivotally connected to the upper end of vertical rods 43, the lower end of 75 which rods are connected to cranks 44 fixed on the shafts 21. It will be obvious that as the cranks rise they will lift the lower ends of the links 42 the pawls 41 thereby riding over the ratchet wheels and as the cranks 80 descend the links will be lowered and the pawls engage with the teeth of the ratchet wheels, advancing the same and through the gearing the rollers. The motion of the rolls 36, 37 is such that a predetermined portion 85 of the clamping strip will be fed over the containers, the feeding of the strip being limited by the ends thereof abutting against a stop or stops 45 extending between the pairs of containers. By forming the peripheries of the rolls as above set forth the clamping strip as it is fed is also longitudinally folded or bent to be substantially of inverted-V shape in cross section.

After the strip has been fed the fed portion is severed by cutter mechanism consisting of a blade or cutter 46 fixed to the head 15 in advance of the lower rolls with which cooperates an adjustably mounted cutter or blade 47 arranged to have reciprocating 90 movement toward and away from the fixed cutter, the cutters being shaped to conform to the folded strip, as clearly shown in the drawings. To impart movement to the reciprocable blades said blades are mounted 100 upon carriers 48 slidably mounted on the head 15, rollers 49 connected to said carriers engaging in inclined runways 50, as clearly shown in Fig. 6, formed between a pair of blocks fixed to the rods or members 110 51 supported in the head 15 to have reciprocating sliding movement transverse to the movement of the reciprocable blades. The bars 51 are actuated by a cam 52 fixed to one of the shafts 21 with which engages a cam 115 follower connected to one end of a rocker arm 53, the other end of said arm having a pin and slot connection 54 with an arm 55 fixed to a shaft 56 mounted in the head 15. Fixed to the shaft 56 is a link 57 having an inclined slot in which engages a head 58 connected to the bars 51. As the lower end of the rocker 53 is pushed forward by the cam rotative movement will be imparted to the shaft 56 by the arm 55 imparting 120 forward movement to the link 57 and thereby pushing the rods 51 forward, such a forward movement of the rods 51 causing the cutters 47 to move toward the fixed cutters 46 and sever the strips.

After the strips have been fed and severed they will lie over the collapsed, or partially collapsed, ends or tops of the containers. To clamp said strips on to the ends of the containers to close and seal the same further movement toward each other is imparted to the clamping bars 16 through the plungers 29, arms 32 and cams 31, such movement of the bars 16 further bending and clenching the strips onto the containers. To prevent the pulling off of the clamping strips from the containers, the bars 16 are provided with projections 58', and as they are moved forward to clamp the strips on to the containers these projections will force portions of the material of the clamping strips into the material of the containers thus firmly securing them to the containers.

The different mechanism of the apparatus is so timed that after a series of containers have been sealed the bars 16 will be released and returned to initial position by the springs, the head will be lifted and the carrier or conveyer with the closed and sealed containers will be advanced and another series of containers presented to the closing mechanism when the operation is repeated.

In the modification shown in Fig. 7, and which may be the preferred form, the head 15 is supported in a fixed position and the carrier or conveyer for the containers is adapted to have movement toward and away from the head. In this construction the rails for the conveyer supporting rollers are supported upon transverse members 59 connected to supports 60 mounted in the base to have vertical movement. The lower ends of the supports have rolls 61 to engage with cams 62 fixed to shafts 63 journaled in the base and actuated from the main driving shaft 10.

It is believed that the operation of the apparatus will be understood from the foregoing and a detail description of the operation of the apparatus is therefore not deemed necessary.

Variations may be resorted to within the scope of my invention.

Having thus described my invention, I claim:

1. In an apparatus of the class specified, the combination of a carrier for a container having an open end; means to collapse the open end of said container; means to feed a metal clamping strip over the collapsed end of the container and longitudinally fold said strip to be substantially of inverted-V shape in cross section; a cutter to sever the fed clamping strip; and means to clamp the strip over the collapsed end of the container and provide the clamping strip with inward extending projections to engage in the material of the container, substantially as and for the purpose specified.

2. In an apparatus of the class specified,

the combination of a carrier for a container having an open end; means to collapse the open end of said container; rolls to feed a metal clamping strip over the collapsed end of the container and longitudinally fold 70 said strip to be substantially of inverted-V shape in cross section; a stop to limit the feeding movement of the clamping strip; means to intermittently actuate said rollers; and a cutter to sever the fed clamping strip; 75 said means to collapse the open end of the container also operable to clamp the strip over the collapsed end of the container to close the same.

3. In an apparatus of the class specified, 80 the combination of a carrier for a container having an open end; a pair of bars mounted to engage at opposite sides of the open end of the container and adapted to have reciprocatory sliding movement toward and away 85 from the container; intermittently operated rollers to feed a metallic clamping strip between said bars and over the end of the container; and a cutter to sever the fed clamping strip; said bars operable to collapse the open end of the container and to 90 clamp the strip onto the collapsed end of the container to close and seal the same.

4. In an apparatus of the class specified, the combination of a carrier for a container having an open end; a pair of bars, one at each side of the open end of the container, mounted to have movement toward and away from the container; means to impart movement to said bars to partially collapse the open 95 end of the container; intermittently operated rollers to feed a clamping strip between said bars and over the partially collapsed end of the container and longitudinally fold 100 said strip to be substantially of inverted-V shape in cross section; and cutting mechanism to sever the fed clamping strip; said bars also operable to clamp the strip onto the collapsed end of the container and having means to force portions of the 105 clamping strip inwardly into the material of the container, substantially as and for the purpose specified.

5. In an apparatus of the class specified, 115 the combination of a carrier for a container having an open end; a pair of bars mounted to have movement toward and away from the open end of the container to partially collapse said open end; a pair of superposed rollers to feed a metal clamping strip 120 between the bars and over the partially collapsed end of the container; and cutter mechanism to sever the fed clamping strip, comprising a cutter fixed forwardly of the lower feeding roll and a cutter forwardly of the upper roll adapted to have movement toward and away from the lower cutter; and said bars also operable to clamp the strip onto the collapsed open end of the 125 container.

- 4
6. In an apparatus of the class specified, the combination of a carrier for a container having an open end; a head above the container; rollers to feed a clamping strip over the open end of the container; ratchet mechanism to rotate the rolls; a rotatable cam; a cam follower connected to the ratchet mechanism to actuate the same and thereby intermittently actuate the rolls; and means 5 carried by the head to collapse the open end of the container and clamp the clamping strip thereto to close the same.
7. In an apparatus of the class specified, the combination of a carrier for a container 10 having an open end; a head above the container; rollers carried by the head to feed a clamping strip over the open end of the container; ratchet mechanism to rotate the rollers; a rotatable cam; a cam follower; a slidably supported rod carrying said cam follower; a link connected to the rod and a ratchet mechanism to actuate the latter and thereby intermittently rotate the rolls; cutter mechanism to sever the fed clamping strip; and means carried by the head to collapse 15 the open end of the container and apply the clamping strip thereto to close the same.
8. In an apparatus of the class specified, the combination of a carrier for a container 20 having an open end; a head above the container; means carried by said head operated to intermittently feed a clamping strip over the open end of the container; a cutter mechanism to sever the fed clamping strip; bars carried by the head to have movement toward and away from the open end of the container; springs to normally maintain the bars in position away from the container; 25 and means to impart movement to the bars against the tension of the spring to collapse the open end of the container and clamp the clamping strip thereto to close the same.
9. In an apparatus of the class specified, 30 the combination of a carrier for a series of containers in juxtaposed pairs; means to feed a clamping strip over each container from opposite sides; a stop between a pair of containers to limit the feeding of the 35 clamping strip; cutter mechanism to sever the fed clamping strip; and means to collapse the tops of the containers and apply the clamping strip thereto to close and seal the same.
10. In an apparatus of the class specified, 40 the combination of a carrier for a series of containers in juxtaposed pairs; means to feed a clamping strip over each container from opposite sides and sever the fed strip; 45 a head above said containers mounted to 50 have movement toward and away from said containers; bars slidably carried by the head to engage at opposite sides of the containers when the head is lowered; and means to impart movement to the bars to collapse the 55 tops of the containers and apply the severed clamping strip thereto to close and seal the containers.
11. In an apparatus of the class specified, 60 the combination of a carrier for a series of 65 containers in juxtaposed pairs; a head above said containers; means to feed a clamping strip over each container from opposite sides and sever the fed strip; bars slidably carried by the head on opposite sides of a pair of 70 containers to have movement toward and away from the latter; springs to normally maintain the bars in position away from the containers; and means to impart movement to the bars against the tension of the springs 75 to collapse the tops of the containers and apply the clamping strip thereto to close and seal the containers.
12. In an apparatus of the class specified, 80 the combination of a carrier for a container 85 having an open top; a head above said container; means carried by said head to collapse the top of the container; means to move the carrier toward the head simultaneously with the actuating means to collapse 90 the top of the container; and means to feed a clamping strip over the top of the container and sever the fed strip; and said means to collapse the top of the container operable to clamp the clamping strip on to 95 the collapsed top of the container to close and seal the same.
13. In an apparatus of the class specified, 100 the combination of a carrier for a container having an open top; a head above said container; bars carried by the head one at each side of the top of the container to have movement toward and away from the container; 105 springs to normally maintain the bars in position away from the container; means to move the carrier toward the head and simultaneously impart movement to the bars to partially collapse the top of the container; and means to feed a clamping strip over the 110 collapsed top of the container and sever the fed strip; and said bars operable to clamp the clamping strip onto the container to close and seal the same.

EDWARD C. ANGELL.
